UNITED STATES PATENT OFFICE.

EDWIN F. NORTHRUP, OF PRINCETON, NEW JERSEY, ASSIGNOR TO AJAX ELECTRO-THERMIC CORPORATION, OF TRENTON, NEW JERSEY, A CORPORATION OF NEW JERSEY.

MULTIPLE-PATH WATER-COOLED FURNACE.

Application filed July 13, 1923. Serial No. 651,398.

The purpose of my invention is to provide multiple paths for water-cooling within conductors which are carrying the primary current for induction furnaces.

5 A further purpose is to concentrate a maximum number of turns per inch in the inductor coil of an induction furnace.

A further purpose is to form the inductor of an induction furnace of a hollow edge-wound conductor having relatively great width extending radially and flattened to secure a maximum number of turns per inch, and to water cool the inductor coil to permit maximum current carrying capacity within 15 each turn so as to obtain a field having high concentration of ampere turns.

A further purpose is to compensate for the high water resistance of the narrow passage provided, by the use of multiple paths 20 of flow for the water, preferably with the electric current flow in series through all the paths but permissibly having these electric paths also in multiple.

A further purpose is, by the combination 25 of edge-wound coil and multiple-path water cooling to overcome previously existing difficulties with low frequency induction furnaces having no inter-threading of transformer iron, concentrating the effective ampere turns upon the charge through increase 30 both of the number of turns per inch and of the effective carrying capacity of each turn.

A further purpose is to apply low frequency inductive heating without necessity 35 for transformer iron interlinkage to the melting out of low-melting point cores from within automobile tires.

Further purposes will appear in the specification and in the claims.

40 I prefer to illustrate my invention by a few applications only, selecting forms which have proved to be practical, efficient and highly advantageous and which at the same time well illustrates the principles of my invention.

Figure 1 is a central section of a furnace to which my invention is applied.

Figures 2, 3, 4 and 10 are corresponding views of slightly different forms.

50 Figure 5 is a longitudinal section of an inductor embodying my invention applied within the interior of a tube.

Figure 6 is a side elevation showing one

of my inductor coils applied to the heating of a tire core. 55

Figure 7 is a section of Figure 6 taken upon line 7-7 looking in the direction of the arrows.

Figure 8 is a section of Figure 7 taken upon line 8-8 and shows additional means 60 for withdrawing the molten core.

Figure 9 is a section of a drum to which several of my coils are applied.

In the drawings similar numerals indicate like parts. 65

In my Patent No. 1,328,336, I have illustrated, described and claimed water-cooled inductors for induction furnaces having a single inlet and single outlet for the water and having a slightly oval or elongated cross 70 section of the individual water-cooling inductors.

It has been generally understood in the past that induction furnaces could not be operated on commercial frequencies for use 75 upon a material which is not itself magnetizable without inter-threading of transformer iron. The reason of this has been that it has been considered impossible to get sufficient input of energy into the secondary from the 80 low frequency primary.

I have discovered that it is possible to so highly concentrate the lines of forces from a low frequency primary as to make commercial frequency practicable for the primaries of induction furnaces without inter-linkage of iron. Two factors have made this possible; the one is the flattening of the section of a hollow inductor so much as to greatly increase the number of turns per unit of 90 length of the furnace coil; and the other is the provision of multiple flow of water through the hollow inductor used so as to permit crowding of the primary conductors to the limit of current which they can carry 95 properly while cold.

The first factor affects the number of turns and the second the number of amperes and each cooperates with the other as a multiplier to secure a maximum of ampere turns with 100 a corresponding maximum of input per unit of length of the coil.

In Figure 1 I have shown a furnace of the stationary cylindrical type having a base 10, an outer protective cylinder 11 which is preferably not only mechanically protective but 105

also heat insulating, an electrically insulating cylinder 12, preferably a fused silica tube and a crucible 13. As used the furnace is preferably packed with a heat insulating powdered refractory 14 such as silica, carbon black or magnesia which forms foundation upon which the crucible rests and fills the space between the crucible and the insulating cylinder 12. This powdered refractory may be withdrawn, permitting withdrawal of the crucible by the removal of a slide 15 upon which the refractory rests and which slide is movable in guides 16.

A top 17 and lid 18 of heat insulating material close the upper part of the furnace.

The induction coil 19 is spiral. It is shown as, and preferably is, connected in series electrically from end to end, the current being applied through terminals 20 and 21.

20 The coil is shown as comprising a helix of copper tubing of very flat section as at 22, through which water is passed in multiple from inlets 23, 24 and through inlet tubes 25 at the top and bottom and out by outlet connection 26.

Where the electrical connection is different from the water connection (i. e., one in series and the other in parallel as here, or with parallel electrical connections not corresponding 30 to the points of water connection) insulating tubing is used for the terminals or is interspersed between the sections to provide insulation.

My invention does not reside in the dimensions selected and will operate with a variety of dimensions. For the purpose, however, of giving one concrete illustration that works satisfactorily I will state that I have used $\frac{3}{4}$ " copper tubing for the inductor with good results, which tubing was flattened to approximately $1\frac{3}{16}$ " in the long dimension of its cross-section and to a width of cross-section but little greater than twice the thickness of the metal walls, giving a cross-section for water flow of nearly one and three-sixteenths by approximately one-thirtieth of an inch. This was a high duty 60 cycle installation.

Since the resistance to water flow through a coil having flow resistance r from end to end varies inversely with the square of the number of sections the division of the coil into two paths in multiple reduces the resistance to one-fourth with increasing benefit where the number of sections is increased.

55 As will be seen there are two paths only for the water here which have proved quite sufficient for a small furnace.

In Figures 2 and 3 the crucible 13' lies lower i. e., closer to the base 10', and there is no opening through the base. In each a plurality of inlets 25 is shown interspersed with outlets 26.

In Figure 2 the winding is continuous for the entire inductor coil, whereas in Figure 3 65 the inductor coil is split up into a plurality

of inductor coils or sections, as in Figure 9, which are both electrically and hydraulically in parallel and which together comprise the complete inductor coil.

In Figure 2 the cross section of the tubing 70 is very much flattened at 22 as in Figure 1, whereas in Figure 3 the tubing is of oval section at 22' corresponding more nearly with the tubing of my patent above mentioned.

The electric current in Fig. 3 is shown as 75 applied in multiple in separate coils corresponding in points of application between the conductors 27 and 28 to the points of application and withdrawal of the inlet and outlet water respectively. Either low frequency or 80 high frequency may be applied through the flattened section of Figure 2, for example, and the multiple water flow cooperate each as a multiplier to increase the concentration of ampere terms to a maximum and hence find 85 special utility in the lower frequencies.

In Figure 4 the electric current is applied in series from conductors 27, 28 and the water flows in multiple through a flattened hollow coil section which may have a single inlet and 90 multiple outlets or a single outlet and multiple inlets as preferred. The inductor is here applied to a pan or kettle of relatively large diameter.

In Figure 5 the coil 19' is shown as inside 95 a tube 29 and as having a plurality of inlets 25 and a single outlet 26 interior to the coil.

In Figures 6, 7 and 8 the coil receives current in series from conductors 27, 28 and has a single inlet or outlet with multiple outlets 100 or inlets as the case may be for water cooling. In this case the coil surrounds a rubber tire 30 upon a rim 31 and is for the purpose of melting out a metal core 32. The metal core is used in molding the tire, and must be removed prior to use. It is normally of lead or of an alloy having a low melting point.

The interior of the tire and the rim are apertured at 33 to provide for removal of the melted core material which will flow out as 110 melted until the level of the top of the rim opening is reached from which point it may be withdrawn by suction through a pipe 34.

In Figure 9 I have shown a plurality of 115 my coils 22² as sections of a complete inductor, distributed along the surface of a preferably iron drum 35 for the purpose of heating the drum and through it controlling the contents of the drum. In each coil or section the electrical current is in series but the several 120 coils or sections are electrically in parallel, one with another. Together they make up the complete inductor coil. This would apply equally well of course, to the heating of electrically conducting contents of a tube, 125 pipe or drum which is itself of non-magnetic or non-conducting material or to heat a solid material at different parts of its length or extent.

In Figure 10 the general construction of 130

Figure 1 is shown with the distinctions that the furnace is shorter and that the pipe is here of circular cross section. One inlet and two outlets here take the place of the two inlets and one outlet of Figure 1.

5 It will be obvious that the word furnace as used herein does not require a melting furnace but will apply also to heating devices where melting does not take place.

10 It will be obvious that the construction and method included herein have all the advantages of the constructions and methods of my previous patents in permitting the use of any standard form of crucible without alteration 15 to provide for interlinkage of transformer iron, that the invention is independent of the size and shape of the article heated whether a conducting container or the material to which the heat is to be directly applied and that the 20 external and internal application of the coil to pipes or tubes will apply equally well to solid material (where outside) drums or other casings or containers.

It will also be evident in view of my dis- 25 closures in my Patents Nos. 1,286,394 and 1,286,395 that any adjustment or correction of power factor may be made in the current supply which may be required.

It will be obvious that various changes may 30 be made in the construction and application of my invention in view of the disclosure herein while taking advantage of all or a part of the benefit of my invention and it is my purpose therefore to include herein all such 35 changes as come within the reasonable spirit and scope of my claims.

Having thus described my invention, what I claim as new and desire to secure by Letters Patent is:—

40 1. In an electric furnace, a hollow inductor furnace coil of highly conducting tubular material, in combination with means for supporting the charge to be heated within the coil and a source of water cooling therefor 45 providing multiple paths from inlet to discharge through different sections of the coil.

2. In an electric furnace, a furnace coil of hollow flat tubing of highly conducting material, the depth of the opening radially being 50 many times its width parallel with the axis, having the turns of the coil close together to provide a maximum of current carrying capacity for a minimum of conductor width, in combination with means for supporting the charge to be heated within the coil and water cooling for the said coil.

3. In an electric furnace, a furnace coil of hollow flat tubing of highly conducting material, the depth of the opening radially being 55 many times its width parallel with the axis, having the turns of the coil close together to provide a maximum of current carrying capacity for a minimum of conductor width, in combination with means for supporting the charge to be heated within the coil 60

and water cooling for the said coil providing multiple paths of water flow through the coil from the point or points of inlet to the point or points of outlet.

4. In an electric furnace, a furnace coil 70 of hollow flat tubing of highly conducting material having the turns of the coil close together to provide a maximum of current carrying capacity for a minimum of conductor width, in combination with means for supporting the charge to be heated within the coil and water cooling for the said coil 75 providing multiple paths of water flow through the coil from the point or points of inlet to the point or points of outlet and a source of low frequency current supply for the coil.

5. In a low frequency induction furnace, the combination of a single layer hollow induction furnace coil flattened to provide great 85 radial depth and narrow axial extension, water cooling for the coil through multiple paths therein, means for supporting the charge to be heated within the coil and a source of low frequency electric current supply in series 90 with the coil.

6. A furnace inductor coil comprising a flat tubular conductor helically wound, adapted to surround the charge and free from 95 interlinkage with transformer iron, in combination with a source of current therefor, means for supporting the charge to be heated within the coil and a plurality of inlet and outlet water cooling connections therefor.

7. A furnace inductor coil, comprising a 100 single layer of coaxial turns each of flattened conductor, having the opening in the conductor of a depth radially of the coil many times the width axially of the coil, having a plurality of inlet and/or outlet water connections 105 for multiple flow of water through different sections of its length, heat insulation within the coil and a crucible within the heat insulation.

8. A furnace inductor coil, comprising a 110 single layer of coil turns each of edge wound conductor flattened to make the opening of depth radially many times the thickness parallel with the axis and a magnetically and electrically conducting cylindrical body 115 within the coil, insulated therefrom and adjacent the inner edges of the coil.

9. As a new article of manufacture, an in- 120 ductor furnace coil of conducting tubing flattened to have a radial depth of tube section many times the width of the section.

10. As a new article of manufacture, an in- 125 ductor furnace coil of conducting tubing flattened to have a radial depth of tube section many times the width of the section and presenting the sides of the turn flat and closely adjacent to the sides of the next turns.

11. In an electric furnace inductor, the combination of a coil of edge-wound flattened tubing having the opening between the side 130

walls of the tubing, approximately equal to the wall thickness of the tubing, in combination with means for passing cooling fluid through the tubing.

- 5 12. In an electric furnace inductor, the combination of a coil of edge-wound flattened tubing having the opening between the side walls of the tubing approximately equal to the wall thickness of the tubing, insulation 10 between the successive turns of the tubing and means for supplying cooling fluid to the tubing, the metal filling substantially half of the entire cross section of tubing, water and insulation.
- 15 13. The method of heating by electrical induction which consists in circulating low frequency current about the charge to be heated, concentrating the ampere turns of the low frequency current applied by utilizing a flat 20 tubular conductor edge-wound to increase the number of turns by reducing the axial length occupied by each turn, winding the turns closer together than the initial diameter of the conductor and water cooling the coil to 25 keep its resistance and temperature low.
14. The method of heating by electrical induction which consists in circulating low frequency current about the charge to be heated, concentrating the ampere turns of the low 30 frequency current applied by utilizing a hollow inductor at a high current concentration wound at a closer spacing than the initial diameter of the inductor tubing and in keeping the temperature and resistance down by passing water through the turns in multiple.
- 35 15. The method of heating by electrical induction which consists in circulating low frequency current about the charge to be heated, concentrating the ampere turns of the low 40 frequency current applied by utilizing a hollow inductor of flattened section having a large radial section depth as compared with the thickness wound at a closer spacing than the initial diameter of the inductor tubing.
- 45 16. The method of obtaining high concentration of ampere turns in an electrical inductor furnace which consists in utilizing a hollow inductor, in passing the electric current through the inductor in series while passing water for cooling purposes through the 50 inductor in multiple and passing current through the inductor at a higher rate than would be permissible with the less effective cooling if the water cooling were applied in series at the same pressure.
- 55 17. The method of obtaining high concentration of ampere turns in an electrically conducting casing of magnetic material within the coil which consists in forming the coil as

a single layer of very flat edge-wound turns having radial depth greatly in excess of their width parallel to the length of the casing, winding the turns very close together and passing current through the turns.

18. The method of heating by electrical induction at a frequency which is not high which consists in concentrating the ampere turns of the current applied by providing a metallic current path of spiral form having for each turn a narrow width axially and a much greater depth radially than its width so as to yield a large cross section per turn of coil length and internally cooling the metal forming the path.

19. The method of heating by electrical induction at a frequency which is not high which consists in concentrating the ampere turns of the current applied by providing a metallic current path of spiral form having for each turn a narrow width axially and a much greater depth radially than its width so as to yield a large cross section per turn of coil length, spacing the paths less along the axis, one from the next than the width of the path and water cooling the path in multiple through the interior, thus reducing the friction to water cooling.

20. The method of heating by electrical induction at a frequency which is not high which consists in concentrating the ampere turns of the current applied by flattening a conducting tube to an interior width across the tube not much in excess of the double thickness of tube wall, in winding the tube edgewise in the form of a coil of but slightly larger interior coil diameter than that of the intended charge and in which the turns are close together to give a maximum of number of turns of hollow conductor and of cross section of metal per unit of single turn coil length and in water cooling the tube through the hollow of the tube thus flattened.

21. In electric induction furnace construction and operation, the method of increasing the current-carrying capacity of hollow water-cooled conductor per unit of single layer coil length which consists in flattening the conductor, winding it edgewise about the space for the charge, with spacing from turn center to turn center less than the initial diameter of the conductor, to increase the number of turns per unit of coil length, thus maintaining the same surface of water contact on the interior for water cooling while reducing the water content and increasing the friction to water passage, and in passing water through various parts of the total inductor in multiple to reduce the fluid resistance met and increase the quantity of water available for cooling.
